UNITED STATES PATENT OFFICE.

HENRY WILLIAM FALKER, OF ASHLAND, PENNSYLVANIA.

GYRATORY SCREENING DEVICE.

1,314,135.

Specification of Letters Patent. Patented Aug. 26, 1919.

Application filed March 16, 1918. Serial No. 222,818.

To all whom it may concern:

Be it known that I, HENRY W. FALKER, a citizen of the United States, residing at Ashland, in the county of Schuylkill and

5 State of Pennsylvania, have invented certain new and useful Improvements in Gyratory Screening Devices, of which the following is a specification.

One object of my invention is to provide a 10 gyratory screening device which will quickly screen and thereby grade coal or the like into various sizes and to so construct my invention that it will be durable and easily operated.

15 Another object is to so construct my invention that a number of superimposed screens can be provided in a single machine and operated from a single vertical shaft.

These objects, and other advantageous 20 ends which will be described hereinafter, I attain in the following manner, reference being had to the accompanying drawings in which—

25 Figure 1 is a central sectional elevation of my invention.

Fig. 2 is a front elevation of Fig. 1 showing the screen frames in section,

Fig. 3 is a sectional plan view taken on the line 3-3 of Fig. 2, and

30 Figs. 4 and 5 are fragmentary elevations showing a modification in certain of the connecting means forming a part of my invention.

Referring to Figs. 1 to 3, inclusive, of the 35 drawings, 1 represents a supporting structure which includes two front uprights 2 and 3^a and two rear uprights 3 and 4. These uprights are preferably made of heavy timber and are connected at points above the 40 ground by longitudinal beams 5 and 6 and transverse beams 7 and 8. The longitudinal beams 5 and 6 support an intermediate transversely extending beam 9. The intermediate transversely extending beam 9 forms a sup-

45 port for two pairs 10 and 11 of poles which are preferably made of wood which is tough and springy. These poles 10 and 11 are preferably secured, at their tops, to the beam 9 by bolts 12 and at their bottoms the pairs 50 of poles are respectively secured to the rear ends of two screening frames 13 and 14, the frame 14 being mounted below the frame 13 and preferably of greater width, as illustrated in Figs. 2 and 3. These frames 13 and 14 slant downwardly from their rear 55 ends to their front ends and are suspended

at their forward ends by two pairs 15 and 16 of flat wide boards which are also preferably made of tough springy wood. The top ends of these boards are secured to the trans- 60 verse beam 7.

The frame 13 includes side pieces 17 and 18 which are spaced apart, the side pieces 17 being positioned above the side pieces 18. In like manner the frame 14 includes side 65 pieces 19 and 20 which are spaced apart, the side pieces 19 being positioned above the side pieces 20.

Screens 21, 22, 23, and 24 extend across the frames and are respectively secured adjacent the bottoms of the side pieces 17, 18, 19, and 20. In this manner the frame 13 supports the two screens 21 and 22 and the frame 14 supports the screens 23 and 24. The mesh of these screens varies in size, the 75 openings of the screen 21 being larger than the openings in the screen 22, the openings in the screen 22 being larger than the openings in the screen 23, and the openings in the latter mentioned screen being larger than the 80 openings in the screen 24. The purpose of this arrangement of screens will be described hereinafter.

A short vertical shaft 25 is mounted in bearings 26, said bearings being secured to 85 a supporting structure, as clearly shown in Figure 1. This shaft 25 forms the operating shaft and, as illustrated, includes a pulley 27 which may be driven from any source of power.

90 Two eccentrics 28 and 29 are secured to the shaft 25 and operate in eccentric straps 30 and 31 which form a part of arms 32 and 33, respectively. The arm 32 is secured to the rear end of the frame 13 substantially 95 midway between its sides and the arm 33 is secured in a similar manner to the rear end of the frame 14. Reinforcing members 34 extend forwardly from the eccentric straps to the frames in a divergent manner and 100 serve as braces for the screens.

With the above construction the rotation of the shaft 25 will, through the medium of the eccentrics 28 and 29 and arms 32 and 33, impart a gyratory movement to both the 105 frames 13 and 14, the poles 10 and 11 and the boards 15 and 16 being sufficiently flexible to permit this gyrating movement. It will thus be understood that if coal, which is to be screened and graded, is placed upon 110 the top screen 21, the movement of the screens will cause the coal to be screened,

that portion of the coal which is small enough to pass through the meshes or openings of the top screen will drop onto the screen 22 and in similar manner the coal 5 which is small enough to pass through the openings of this screen will drop upon the screen 23 and so on to the screen 24.

Furthermore, since the screens and frames are inclined, as illustrated, the 10 screened material can be easily taken off from the front end. Also, by having the side pieces of the frames spaced apart the material within the frames can be readily observed. Also, by having the screens of 15 various widths, as illustrated, all of the material passing from the top frame screens will fall upon the screen 23.

In order to support the various screens at different points throughout their length, 20 I provide transverse bottom bars 35 which are secured at their ends to the side pieces of the frames.

By providing the wide boards 15 and 16 I secure a durable suspending structure and 25 if desired instead of having these boards secured directly to the transverse beam 7 they can be provided with a ball-and-socket connection 36, such as shown in Fig. 4, said ball-and-socket connection including a 30 bracket 37 which can be secured to the transverse beam 7. In this manner all of the boards 15 and 16 can be connected if desired and in which case they will have a free rocking or springing movement due to 35 the action of the eccentrics.

In similar manner the poles 10 and 11 can be secured by a ball-and-socket connection 38, as shown in Fig. 5, said connection including a bracket 39 designed for attachment 40 to the intermediate transverse beam 9.

While I have described my invention as

taking a particular form, it will be understood that the various parts of my invention may be changed without departing from the spirit thereof, and hence I do not limit 45 myself to the precise construction set forth, but consider that I am at liberty to make such changes and alterations as fairly come within the scope of the appended claims.

Having thus described my invention, 50 what I claim as new and desire to secure by Letters Patent is:

1. A screening device including a screen; comparatively wide means for suspending one end of the screen and yieldable practically entirely in the direction of the length of the screen; means for suspending the opposite end of the screen, said latter means being readily flexible in all horizontal directions; and means for gyrating said latter 60 mentioned end portion of the screen, substantially as described.

2. A screening device including a screen; comparatively wide means for suspending one end of the screen and yieldable practically entirely in the direction of the length of the screen; means for suspending the opposite end of the screen, said latter means being readily flexible in all horizontal directions; a vertical actuating shaft; and an 65 eccentric secured to said shaft and operatively connected to said latter mentioned end of the screen whereby the latter is gyrated, substantially as described.

In testimony whereof I have signed my 70 name to this specification in the presence of two subscribing witnesses.

HENRY WILLIAM FALKER.
